FIG. 6.

UNITED STATES PATENT OFFICE.

ELIEL L. SHARPNECK, OF CHICAGO, ILLINOIS.

APPARATUS FOR THE TREATMENT OF ORES.

SPECIFICATION forming part of Letters Patent No. 697,178, dated April 8, 1902.

Application filed April 25, 1901. Serial No. 57,445. (No model.)

To all whom it may concern:

Be it known that I, ELIEL L. SHARPNECK, a citizen of the United States, residing at Chicago, in the county of Cook and State of Illinois, have invented a new and useful Improvement in Apparatus for the Treatment of Ores, of which the following is a specification.

My invention relates to improved apparatus for use in carrying on the leaching process of extracting the values from ores, and more especially for use in the treatment of ores containing carbonate or oxid of copper.

My object is to provide apparatus of improved construction for hastening the leaching and filtering operations and rendering the practice more thorough and economical.

In the drawings, Figure 1 is a diagrammatic view of apparatus with my improvements applied; Fig. 2, a vertical section of a leaching-tank, and Fig. 3 a similar view of a filtering-tank, both employed in carrying on the leaching and filtering of the ore; Fig. 4, an enlarged and broken section of a jet-pump; Fig. 5, a transverse section of a precipitating-tank, the section being taken on line 5 in Fig. 6; and Fig. 6, a broken longitudinal section taken on line 6 in Fig. 5.

A is a leaching-tank; B, a filtering-tank; C, a precipitating-tank; D, a storage-tank, and E a sump or settling tank.

On the tank A is a pair of standards *a a*, provided at their tops with pulleys or sheaves *b*. The leaching-tank is formed, preferably, as shown in Fig. 2, with a hopper-shaped false bottom *c* and a cover or cross-piece *d*, presenting a central vertical guide-opening *d'*.

F is a jet-pump having a chamber *e*. Extending into the side of the chamber is a nozzle *f*, terminating at the center of the chamber and upturned to discharge in a direction longitudinal of the chamber. Connecting with the pipe or nozzle *f* is a rubber hose *f'*, extending from a steam-supply pipe *f''*, provided with a valve *f'''*. Extending downward from the lower end of the chamber *e* is a short pipe *g*. A pipe *h* extends upward from the chamber *e* and is provided at its upper end with a valve *h'*. Communicating with the pipe *h* below the valve *h'* is a branch pipe *h''*, provided with a valve *h'''*. Extending downward from the valve *h'''* parallel with the

pipe *h* is a pipe *h⁴*, terminating in a plane preferably just below that of the jet-pump *F*. Extending from the top of the pipe *h* is a hose-pipe *i*, which terminates over and empties into the filtering-tank *B*, and extending over the pulleys *b* are cords *k*, carrying counterweights *k'*. The counterweights counterbalance the jet-pump and parts carried thereby, whereby they may be raised and lowered with relation to the tank *A* and remain in adjusted position. The hose *i* above the tank *B* is held in adjusted position by suspending means *l*, and above the tank *A* it is suspended by a cord *m*, passing over a pulley *m'* and carrying a counterweight *m''*.

The filtering-tank *B* is formed, preferably, as illustrated in Fig. 3, with the flat bottom *n* and false hopper-shaped bottom *n'*, provided with numerous perforations *n''*. Between the bottoms *n n'* is a chamber *n³*. At the center of the bottoms *n n'* is an outlet-opening *n⁴*, leading to a trough *n⁵* and closed by a plug *n⁶*. Extending from the chamber *n³* of the vat *B* is a pipe *p*, having a valve *p'* and communicating with a hose-section *p''*, extending at its end downward to empty into one end portion of the precipitating-tank *C*.

The tank *C* is divided by partitions *q* into compartments *q' q'' q'''*, each partition being provided at the center of its upper edge with an overflow *q⁴*. This precipitating-tank is of a novel construction, forming the subject-matter of a concurrent application filed by me the 25th day of April, 1901, Serial No. 57,446. It will suffice to say in the present connection that it is formed with longitudinally-extending shoulders *r r* and longitudinally-extending shoulders *r' r'* at a higher level than the shoulders *r*. On one of the shoulders *r* at one side of the tank *C* is a conductor rod or plate *s*, communicating with the negative pole of an electric generator *G*, and on one of the shoulders *r'*, preferably at the opposite side of the tank, is a conductor rod or plate *s'*, communicating with the positive pole of the electric generator *G*. Extending across the tank and resting upon the shoulders *r'* are transverse rods *t*, which in this way rest at one end upon the conductor *s'*, and between the said rods *t* are rods *t'*, resting at opposite ends on the shoulders *r*, whereby they rest at one end in contact with the electric conductor

s. Suspended from each of the rods is a sheet-lead apron or plate, the plates extending at their lower ends nearly to the bottom of the tank. The sheets t^2 form the anodes and the 5 sheets t^3 form the cathodes. There are an equal number of anodes and cathodes in each of the compartments of the vat, and suspended around the cathodes in the manner shown are bags t^4 , of porous cloth, forming pockets. At 10 the end of the tank C is an overflow-trough q^5 , emptying into the sump-tank E. Extending from the lower side of the tank C to the tank E is a valved pipe q^6 , which may connect with each of the compartments q^1 q^2 q^3 . A 15 pipe H extends from near the bottom and center of the sump-tank upward to empty into the tank D, as shown. Interposed in the pipe H is a jet-pump H', constructed like the jet-pump F and communicating with a steam-supply pipe H^2 , provided with a valve H^3 . Extending from the bottom of the storage-tank D is a pipe I, having an interposed valve I' and terminating over the leaching-tank A. 20

The operation is as follows in the treatment 25 of ore containing oxid or carbonate of copper: After being pulverized to about forty or fifty mesh the ore is fed into the leaching-tank A, sufficient water being added to make the mixture flow easily. Enough of a suitable acid 30 is then poured into the mixture for carrying out the leaching process. It may be stated that in the use of the acid I prefer to employ I provide one and a half times as much acid in pounds as there are pounds of copper in 35 the mass of ore to be treated. Previous to starting the jet-pump F the valve h' is closed and the valve h^3 is opened. The pump is then raised until the lower end of the pipe g is at the top of the tank A, and the valve f^3 is 40 then opened to admit steam. The steam passes from the nozzle f upward through the pipe h , thence through the pipe h^2 and valve h^3 , and downward through the pipe h^4 . After the jet-pump is started it is gradually lowered 45 until it reaches the position shown, which causes the lower end of the pipe g to reach nearly to the bottom of the tank. The operation of the jet-pump causes the mixture in the tank A to be raised by the suction action 50 effected by the jet of steam and discharged again downward through the pipe h^4 . Thus a constant rapid circulation is kept up to agitate the liquid contents of the leaching-tank, and the contact of the mixture with steam 55 causes it to be raised gradually to a high temperature. This heating of the mixture renders the action of the acid very rapid, so that in a comparatively short time all or very nearly all of the copper will go into solution. 60 In practice with apparatus constructed as described I cause the jet-pump to operate until the mixture is raised to a temperature of about 200° Fahrenheit, which takes on the average about twenty minutes, by which time 65 all, or at least ninety per cent., of the copper will have gone into solution. When this operation is completed as described, the valve

f^3 is shut off, the jet-pump raised, and the solution allowed to settle a few minutes. In a very short time the pulp will settle to the bottom of the tank, causing the copper solution to remain on the top. The valve h^3 is then closed and the valves h' f^3 opened to cause the steam to discharge from the jet-pump through the pipe i . The pump is then 70 gradually lowered to thus raise and transfer the copper solution from the tank A through the pipe or hose i to the filtering-tank B. When nearly all the solution has been thus transferred from the pulp, the pump is stopped. 75 The valve p' is left open, whereby the solution as fast as it is filtered and enters the chamber n^3 will pass downward to the precipitating-tank C. The construction of the tank C with its compartments q^1 q^2 q^3 causes the 80 solution to flow downward as it enters from the pipe or hose p^2 and gradually fill the first compartment, then overflow through the recess q^4 into the second compartment. In the second and third compartments I prefer to 85 provide baffles q^7 , which direct the current as it enters through the overflow q^4 downward, so that it will all rise in close proximity to the cathodes t^3 . In practice I prefer to so regulate the voltage and amperage of the current that in the electrolytic action metallic 90 copper as fast as it accumulates upon the cathodal plates will drop off into the pockets formed by the bags t^4 . In the precipitating-tank all or all but a comparatively small percentage of the copper carried in solution will 95 be extracted therefrom, and very little else but diluted acid will flow through the overflow-trough q^5 into the sump-tank E. When 100 all of this charge of the leaching-tank that has been pumped from the pulp therein has passed into the precipitating-tank, what remains in the said precipitating-tank may be drawn off into the sump-tank through the valved pipe q^6 . Nearly all of this solution 105 thus drawn off will have been freed of the copper. As the acid flows into the sump-tank E it is withdrawn by means of the jet-pump H' and deposited in the storage-tank D to be used over again. After the solution 110 has been drawn off and filtered and the copper contained therein has been precipitated as described water in sufficient quantity 115 may be poured into the leaching-tank A and the jet-pump started again to form a new solution. All of this solution, with the pulp, may then be drawn off by means of the jet-pump to the filtering-tank B or another similar tank 120 and filtered and washed by the addition of more water at the filtering-tank until the pulp or tailings contain no more copper to be saved. The second solution may be passed through the same or another precipitating-tank C, and instead of being drained off into the storage-tank D it may be caused to flow into a separate 125 storage-tank, to be used in the place of clear water in first diluting the next charge of ore in the leaching-tank. It will be understood that the acid is used over and over again 130

and its strength increased from time to time as required. Of course as many leaching, filtering, precipitating, sump, and storage tanks may be employed as desired for mills of different capacities, and it is desirable to provide more storage than leaching or filtering tanks, so that the weakened acid solutions need not be mixed with the stronger before entering tanks in which the ores are treated.

10 It will be understood that the apparatus forming the subject of my present invention is not necessarily limited to use in the treatment of copper ores, because it may be employed with equal advantage in the treatment of gold and silver bearing ores in the practice of the cyanid or any other leaching process.

15 What I claim as new, and desire to secure by Letters Patent, is—

20 1. As a means for facilitating the dissolving of the values in ores, the combination of a leaching-tank, a conduit leading from and discharging directly into the tank, and means in the conduit connected with a heating-medium supply for agitating, circulating and heating the liquid contents of the tank.

25 2. As a means for facilitating the dissolving of the values in ores, the combination of a leaching-tank, a conduit leading from and dis-

charging into the tank, and a jet-nozzle connected with a steam-supply and discharging directly into the conduit whereby the liquid contents of the tank is agitated, circulated and heated.

3. The combination with a leaching-tank of an agitating device for the liquid contents thereof comprising a conduit leading from and returning to the tank, a jet-pump interposed in said conduit for circulating said liquid contents through it and means for raising and lowering the jet-pump and conduit with relation to the said leaching-tank.

4. The combination with a leaching-tank and a filtering-tank of a valved conduit extending between said tanks, a valved branch pipe extending from said conduit below the valve therein back to the leaching-tank and a jet-pump interposed in said conduit between the said leaching-tank and branch pipe, whereby the liquid contents of the leaching-tank may be circulated through said conduit and branch pipe or transferred through said conduit to the said filtering-tank, substantially as described.

ELIEL L. SHARPNECK.
